UNITED STATES PATENT OFFICE.

FREDERICK JAMES MITCHELL, OF NEW YORK, N. Y.

AIR-FORCING DEVICE FOR ATOMIZERS.

SPECIFICATION forming part of Letters Patent No. 585,220, dated June 29, 1897.

Application filed December 10, 1895. Serial No. 571,629. (No model.)

To all whom it may concern:

Be it known that I, FREDERICK JAMES MITCHELL, a citizen of the United States, and a resident of the city, county, and State of New York, have invented certain new and useful Improvements in Apparatus for Forcing Air, of which the following is a full, clear, and exact description, reference being had to the accompanying drawings, forming part of this specification.

My invention relates to apparatus for operating a pneumatic device—such, for instance, as an atomizer—by the movement of a door or some equivalent device; and the object thereof is to provide a simple, reliable, and substantially noiseless apparatus of practically universal applicability.

To this end the invention consists in the arrangement and combination of parts herein-after described, and specifically pointed out in the claim.

In the drawings, Figure 1 is a view in elevation showing my improved apparatus connected with an atomizer. Fig. 2 is a plan view thereof on a larger scale, and Fig. 3 is a plan view showing a modified arrangement in which the cylinder and its connected parts are shown secured to the door.

Similar letters of reference are used to indicate corresponding parts in all the views.

The air cylinder or pump A is provided with a piston B, suitably mounted on the hollow piston-rod b. The cylinder and piston are pivotally attached to a suitable support, which may be either the door-jamb X, as shown in Figs. 1 and 2, or the door Y, as shown in Fig. 3, by the pivot c, which passes through the piston-rod and through the lugs c' of the plate C, the latter being secured or otherwise affixed to the said support. A vent b' communicates with the air-passage b², which runs longitudinally through the piston-rod from the vent b' to the inner end of the rod behind the piston. A tube D connects the vent b' with the pneumatic device E, which, as shown, is an atomizer of ordinary construction arranged to discharge a liquid or powdered substance when a current of air is forced through the tube D. This atomizer or equivalent device E may, as will be perceived, be situated at a considerable distance from the point at which the cylinder and its operating mechan-

ism are located. To the said support is also secured a plate F, in which is fixed the depending pin f, which serves as a pivot for the lever G, which at its opposite end is pivotally connected with the end of the cylinder A by the pin g, which passes through the thimbles b³, secured to the cylinder-head. The coil-spring H is carried by the pin f, one end of the spring being firmly secured to the pin and the other end thereof passing under and behind the lever G, so that the spring will tend to carry the lever away from the support, as shown in full lines in Figs. 2 and 3. The movement of the lever G may be limited in that direction by the stop b⁴ on the piston-rod b, Fig. 2. A pin I is securely fixed to and is carried by the other member of the support, which may be either the door, as shown in Figs. 1 and 2, or the door-jamb, as shown in Fig. 3, and a roller i is preferably mounted on said pin in such a position that it will engage with the lever G when the door is closed and in such a manner that it will rotate freely on its axis. This roller is preferably made of wood or some non-metallic substance to render its action as noiseless as possible.

Referring to Figs. 1 and 2, the operation of my invention is as follows: When the door is shut, as shown in Fig. 1, the roller i will be in contact with the lever G and will hold the cylinder A and the lever G toward the door-jamb, as shown in dotted lines, Fig. 2. When the door is opened, the roller i will be carried with it and the spring H will swing the lever G on its pivot, carrying the lever and the cylinder A into the position shown in the full lines, Fig. 2. The piston B will thus be carried toward the forward end of the cylinder and the space behind the piston will fill with air, which is drawn through the tube D and the passage b² in the piston-rod. As the door Y is opened beyond the position shown in Fig. 2 the roller i will be carried away from the lever G, but the lever and cylinder will be held in the position shown by the engagement of the stop b⁴, Fig. 2, or the piston, Fig. 3, with the cylinder-head. When the door is closed, the roller i will be brought into engagement with the lever G again and will carry the lever and cylinder into the position shown in dotted lines, Fig. 2, forcing the piston toward the bottom of the cylinder

and forcibly expelling the air contained ther-in through the passage b^2 and pipe D across the discharge-tube of the atomizer E, thus spraying into the room or apartment where 5 the atomizer is located a quantity of the liquid or other substance therein contained.

In the modified arrangement shown in Fig. 3 the cylinder and its connected parts are supported on the door instead of on the door-jamb and the operating-pin I is mounted on the door-jamb. When the door is opened, 10 the resulting disengagement of the lever G and roller i permits the spring F to carry the cylinder into an angular position with the door to charge the cylinder, as before de- 15 scribed, and the engagement of the roller i with the lever G forces the cylinder into the position shown in dotted lines, thereby dis-charging the cylinder to operate the atomizer.

20 If desired, a short section of rubber tubing may be substituted for the roller i.

It will be observed that this invention is peculiarly adapted for use in automatic dis-infecting systems such as are now in general 25 use in the large cities, as any desired quan-tity of the disinfectant or deodorant used in the system may be discharged into any room or apartment by the closing of a door or other similar object.

30 I do not wish it understood that I claim, broadly, herein the combination of an atom-izer and air-forcing cylinder adapted to be operated by the movement of a door, since such a device is shown in my previous United 35 States Letters Patent, No. 371,615, dated Oc-tober 14, 1887, and No. 435,043, dated August 26, 1890; but my improved apparatus pos-sesses very decided advantages over these former devices, because the cylinder can be 40 placed either on the door or on the door-jamb, and it may be located at any point or in any

position either inside or outside the door and either on the side or on the top of the door, as desired, while in the previous structures the cylinder could be placed on one side only 45 of the door, at its top and within a few inches of its hinges. They would not operate if placed in any other position, and this pre-cluded their use in places where the door did not extend to the top of the casing, a con- 50 struction very common in closets and bath-rooms.

Another advantage is that the device herein shown and described is practically noiseless in operation, which is a practical considera- 55 tion of great importance.

Another advantage of the present apparatus over that shown in my said Patent No. 435,043 is that it is operated by closing instead of 60 the opening of the door.

Having thus shown and described my in-vention, what I claim as new, and desire to 65 secure by Letters Patent, is—

In air-forcing devices for operating atom-izers and the like, the combination with suit- 65 able supports such as a door and its jamb, of the cylinder A provided with the piston B, an arm G pivotally connected with said cyl- 70 inder, said cylinder and arm being secured to one of said supports, a spring arranged to normally hold said cylinder and arm away from and at an angle to their support, and a projection secured to the other support so as to engage with the arm G, when the door or equivalent support is closed, and cause the 75 expulsion of the air in said cylinder, substan-tially as shown and described.

FREDERICK JAMES MITCHELL.
